(**) Term: **14 Years**(21) Appl. No.: **29/406,833**(22) Filed: **Nov. 18, 2011****Related U.S. Application Data**

(63) Continuation of application No. 11/425,298, filed on Jun. 20, 2006, now Pat. No. 8,061,775.

Primary Examiner — Mimosa De
(74) **Attorney, Agent, or Firm** — Jones, Walker, Waechter, Poitevent, Carrere & Denegre, LLP(51) **LOC (9) Cl.** ..... **06-01****CLAIM**(52) **U.S. Cl.** **D6/501**

I claim the ornamental design for a pair of armrests for a chair or the like, as shown and described.

(58) **Field of Classification Search** D6/334–336,
D6/364, 365, 366, 367, 374, 375, 379, 500,
D6/501, 502; 297/411.29, 411.35, 285, 340,
297/341, 300.1–300.5, 452.13, 452.29**DESCRIPTION**

See application file for complete search history.

FIG. 1 is a front perspective view of a pair of armrests for a chair or the like embodying the present invention; FIG. 2 is a front view of the pair of armrests of FIG. 1; FIG. 3 is a rear view of the pair of armrests of FIG. 1; FIG. 4 is a left side view of the pair of armrests of FIG. 1; FIG. 5 is a right side view of the pair of armrests of FIG. 1; FIG. 6 is a top view of the pair of armrests of FIG. 1; and, FIG. 7 is a bottom view of the pair of armrests of FIG. 1. The broken lines shown herein are for illustrative purposes only and form no part of the claimed design.
